UNITED STATES PATENT OFFICE.

OSCAR ROESEN, OF NEW YORK, N. Y., ASSIGNOR TO R. HOE & CO., OF NEW YORK, N. Y., A CORPORATION OF NEW YORK.

INKING MECHANISM FOR PRINTING MACHINES.

Application filed October 13, 1919. Serial No. 330,225.

To all whom it may concern:

Be it known that I, OSCAR ROESEN, a citizen of the United States, residing at New York city, county of Kings, and State of New York, have invented certain new and useful Improvements in Inking Mechanism for Printing Machines, fully described and represented in the following specification and the accompanying drawings, forming a part of the same.

This invention relates to improvements in inking mechanism for printing machines and is designed particularly for use with the type of inking mechanism shown in United States Patents No. 1,214,856, February 6, 1917 and No. 1,311,198, July 29, 1919, both to Bruce C. White.

In the type of inking mechanism shown in these patents, ink is supplied through a series of separate conduits, one conduit being provided for each column or other desired section of the form to be inked, and the ink is delivered under pressure to the conduits and in regulated quantity by a plurality of pumps, one pump being provided for each conduit. In this inking mechanism there is provided a reservoir located adjacent the distributing cylinder or the form cylinder, or other surface to which the ink is to be forced. The pumps are located in this reservoir and means are provided for independently varying the adjustment of each of the pumps, so that the supply of ink delivered to each column or other section of the form may be varied as desired. These adjusting devices are located closely adjacent the pumps, being as shown in these patents, in the reservoirs, and the adjustment is effected by the operator at the reservoir.

Where two or more printing couples are employed, as in the large rotary multicouple machines, each couple is provided with one of these reservoirs and the inking mechanism contained therein then briefly referred to. In the making of adjustments, therefore, the operator has to move around the machine from one couple to the other to make his adjustments. It is desirable, therefore, that means be provided whereby the pumps of all the reservoirs may be adjusted from a central point which may be

located at any convenient and desired part of the machine, as for instance, the folder, whereby the pressman when not satisfied with the character of printing as the web reaches the folder can adjust the necessary ink pumps to the required or desired degree and inking of any particular column or section which may require such regulation. It is further desirable that an independent adjustment of the ink at or adjacent the pumps be maintained so that an adjustment can be made there.

It is the especial object of the present invention to produce an inking mechanism for printing machines, each couple when more than one couple is employed being provided with an inking mechanism embodying separate conduits, one for each column or other section of the form, with means for feeding ink to the conduits, and a central controller station located at a distance from the ink supplying means for adjusting or regulating the quantity of ink supplied from the conduits. A further object of the invention is to produce such a construction which will combine a distant adjustment with an adjustment close to or adjacent the printing couple, and a further object of the invention is to produce an efficient construction for such purpose which comprises as small a number of parts as possible and of simple character, so as not to readily get out of order.

With these and other objects not specifically referred to, the invention consists in certain novel parts and combinations, which for a full understanding thereof will be described in connection with the accompanying drawings in which:—

Figure 1 is a diagrammatic side elevation of a two couple printing machine embodying the invention in a preferred form.

Figure 2 is a side view partly in section and partly broken away along the distributor, showing the arrangement of the conduits as they come from the reservoir.

Figure 3 is a detail sectional view showing a form of nozzle which may be used for distributing the ink on the distributor.

Figure 4 is a detail sectional view on an enlarged scale through one of the reservoirs.

Figure 5 is a similar view, partly broken

away, showing the driving mechanism for operating the pumps.

Figure 6 is a detail sectional view of part of the controlling or adjusting mechanism which is located at a distance from the pumps.

Referring now to these drawings, the invention has been illustrated as employed with a rotary printing machine having two printing couples, each of which is provided with a reservoir in which operate the ink pumps and a control station located at the folder. It will be understood, however, that the invention has been designed for and may be used with a single couple machine and that the control station may be located at a point in the machine other than the folder, if so desired, and with other feeding devices.

20 In these drawings, one of the printing couples includes the form and impression cylinders 1, 2, with the distributor 3 and a train of ink distributing rolls 4, this couple being inked from a reservoir 5. The other couple includes the impression cylinder 6, form cylinder 7, distributor 8, and train of ink rolls 9, this couple being inked from the reservoir 10. After printing the web W is led to a folder 11 of any suitable character and at the folder are positioned the control stations, preferably one for each reservoir marked 12 and 13.

30 The inking mechanisms employed are the same for all the couples, and a description 35 of one will suffice for all.

In the particular construction illustrated, each inking mechanism will include a reservoir 15 having a top 16 and a bottom 17. The bottom of the reservoir is apertured 40 to receive a plurality of ink conduits 18, the conduits extending through packing 19 so as to be ink tight. These conduits are provided preferably in such numbers that there is a conduit for each column or other section 45 of the form or forms to be inked, the conduits in the particular construction illustrated being 32, to ink 32 columns. These conduits lead to the distributor as 3, being carried beyond the reservoir so as to be beneath 50 the distributor as shown in Fig. 2, in a frame or box 20, one wall of which is formed with a distributing nozzle indicated generally at 21 by which the ink is delivered to the distributor or other ink receiving 55 surface. While the nozzle shown in Figs. 2 and 3, is the preferred one, it will be understood that the ink may be delivered from the conduits to the distributor in any desired manner, and with any desired form of 60 nozzle.

The ink is forced to the conduits in regulated quantities through a series of pumps, one such pump being provided for each conduit. The pumping mechanism may be of 65 various forms and may be operated in va-

rious ways. One that has worked well in practice is that illustrated in the drawings, in which there is provided in the reservoir a frame 22 mounted to have a sidewise sliding movement in suitable guides 23, one of which is shown in Fig. 5. This frame is provided with suction and discharge ports 24, one of these ports being provided for each of the conduits 18. Working in the frame and in each of these ports is a valveless plunger pump having a plunger in the form of a rod 25 which intermediate its end is provided with an operating collar 26 fast thereon. These pumps are operated in any desired manner, being given a vertical movement for suction and discharge, and the frame 22 is given a sidewise sliding movement alternately to bring the ports 24 into communication with the ink in the reservoir for suction and with conduits 18 for discharge. As shown, this is effected by providing a second frame 27 having apertures 28 through which work the upper ends of the plunger rods 25. This frame 27 is grooved, preferably at two points, to receive eccentric shafts 29, 30, which at their ends carry eccentric heads 31 fast on the frame 27. These shafts are driven in any suitable manner, as from a power shaft 32 having a miter gear 33 meshing with a miter 34 on a short shaft 35. The other end of this shaft 35 carries an intermediate gear 36 which meshes with gears 37 on the ends of the shafts 29, 30, before referred to.

Each of the plunger rods 25 above the frame 27 is provided with a spring 38, taking between the top of the frame and a stop collar 39 fast on the rod. The frames 22 and 27 are preferably connected with each other by a supporting rod or bar 40, through which the sliding sidewise movement is given to the frame 22. As the eccentric shafts rotate, the frame 22 is given a sidewise movement to bring the ports 24 into communication with the bottom of the reservoir. As the movement of the shafts continues the frame 27 is lifted and this movement raises the plungers through the springs 38 the extent of this movement depending on the position of certain stops hereinafter referred to. Any further movement of the eccentric is compensated for by the springs 38. As the shafts continue their further movement and the frame 27 starts downward it contacts with the collars 26, before referred to, and as at this time the frame 22 has slid sidewise so as to bring the discharge ports 24 into line with the conduits 18, a further movement of the eccentric causes the plungers to start to move down and force the measured quantity of ink into the conduits.

In accordance with the invention, means are provided whereby the upward or suction movement of the plungers may be varied so

that they will take up on the suction stroke a varying quantity of ink, and means will be provided whereby this regulation of the plunger movement may be controlled both at 5 the pumps or at any other desired point of the machine, at a distance from the pumps. Various constructions may be provided whereby this may be effected. In the particular construction illustrated, the top 16 of the 10 reservoir is formed with a plurality of downwardly extending projections 41 which are recessed to accommodate stops 42, the position of which limits the suction stroke of the plungers. These stops are in the form of 15 sliding rods and in recessed portions of the projections 41 these rods are provided with springs 43 taking against the bottom of the recessed portions of the projections at one end and against collars 44 fast on the 20 rods at the other ends. The tendency of the springs is to throw the stops up. This upward movement of the stops is limited by adjusting screws 45, these screws being threaded through blocks 46, and the screws 25 provided with heads 47 by which they can be adjusted in the blocks so as to cause the stop rods 42 to stop their upward movement at a desired point to provide for the necessary suction stroke of the plungers. The 30 plunger movement can thus be regulated at the pumps.

Various constructions may be employed for effecting the regulation of the plunger movement at some point in the machine 35 distant from the pumps. In the particular construction illustrated, this distance regulation takes place from the folder and at the folder there are provided what may be termed controller stations from which the 40 adjustment of the pumps may be effected. The particular means for carrying out this may be widely varied, but in the particular construction illustrated, it is effected by a movement of the adjusting screws 45, before 45 referred to. As shown, the blocks 46 are pivoted on studs 48 and each block is provided with a downwardly extending projection or ear 49 in which is secured a mechanical connection leading to the controller station, this connection, in the present 50 instance, being a wire 50, one of these wires 50 being provided for each adjusting screw. These wires 50 pass over suitable guide rolls 51 (see Fig. 1), which are preferably 55 flanged to and over a flanged guide roll 53 at the controller, and these wires are operated from the controller in any suitable manner to give them the required movement for operating the adjusting screws 45.

60 While various constructions of controllers may be employed, as shown, there is provided a box 54, it being understood that one of these controllers is provided for each inking mechanism. This controller box has 65 a top 55 which is apertured to receive ad-

justing screws 56, these adjusting screws being the same in number as the adjusting screws 45, before referred to. Mounted in the box beneath the top thereof are brackets 57 in which are pivoted on pivots 58 levers 70 59, one lever being provided for each screw. One arm of these levers, as 60, contacts with the lower end of the adjusting screw 56. The other arm 61 of the lever 59 is tapped to receive a screw bolt 62 held in position by 75 locking nuts 63, and the other ends of the wires 50 are attached to these bolts.

It will be seen that with this construction by operating the adjusting screws 56 the lever 59 is rocked which in turn through 80 the wires 50 rock the blocks 46, thus moving the screws 45 downwardly thereby forcing the stops 42 downwardly and limiting the extent of the upward or suction stroke of the plungers 25, so as to regulate the amount 85 of ink supplied to the particular conduit whose pump has been adjusted. On releasing the adjusting screws 56, the springs 43, on the stops 42 act to force the stops upwardly to the position previously occupied 90 by them before the adjustment was changed by manipulating the screws 56. A very simple and efficient construction is thus provided for regulating the pumps from any desired point in the machine. If desired the 95 adjustment at the pumps may be omitted, but preferably, as before stated, thus adjusting means will be employed.

In the construction illustrated in the drawings, the pumps and conduits are arranged, preferably as shown, in what may be termed sets, one set supplying eight different columns or sections of the form, that is the supply of ink necessary for printing one page. Machines constructed in accordance with the invention may include devices whereby the ink supplied by each set 100 of pumps may be simultaneously varied, so that, if desired, the ink supply for a whole page may be simultaneously cut down or 105 increased. Constructions for effecting this result are shown in the drawings, in which each of the sets of pumps is provided with such an adjusting mechanism. As illustrated this adjusting mechanism comprises 110 a controller 65, one controller being provided for each set and being identical in construction and manipulation. As shown, this controller is in the form of a sliding frame or bar, the frame being arranged to 115 slide in a groove or slot 66 in a plate 67 mounted on the bottom 17 of the reservoir, before referred to. This controller 65 is provided with ports 68 through which the maximum amount of ink to be delivered by 120 the pump may be passed to the conduits 18. The controller frame is also provided with what may be termed by-pass ports 69 in the form of shallow grooves separated from the 125 ports 68 by narrow ridges 70. By shifting 130

this controller frame, as shown in Fig. 5, the ports 68 and 69 are shifted relatively to the port 24, so that only a portion of the ink passes from the ports 24 to and through 5 the ports 68 to the conduits, a certain amount of the ink being diverted through the port 69 back into the reservoir, the amount of ink thus diverted and returned depending on how much of the area of port 69 is 10 brought into communication with the discharge port 24.

While the invention has been shown and described in its preferred form, it will be understood that various forms of feeding 15 mechanism may be employed and various connections between the feeding mechanism and the controller station or stations without departing from the invention, and it will be understood that such changes and variations are within the scope of the invention. 20

What I claim is.

1. In an inking mechanism, the combination of a plurality of separate ink delivery conduits for delivering an independent supply 25 of ink to different columns or sections of the form, a plurality of pumps one for supplying each conduit with ink, a controller located at a point remote from the pumps, and mechanical connections from 30 the controller to the pumps for regulating the ink delivered by them.

2. In an inking mechanism, the combination of a plurality of separate ink delivery conduits for delivering an independent supply 35 of ink to different columns or sections of the form, a plurality of pumps one for supplying each conduit with ink, a controller located at a point remote from the pumps, and mechanical connections from 40 the controller to the pumps for independently regulating the ink delivered by them.

3. In an inking mechanism, the combination of a plurality of pumps for delivering ink under pressure in regulated quantities, 45 a controller located at a point remote from the pumps for regulating the ink delivered by them, and mechanical connections from the pumps to the controller.

4. In an inking mechanism, the combination 50 of a plurality of pumps for delivering ink under pressure in regulated quantities, a controller located at point remote from the pumps, said controller having a plurality of adjusting devices, one for each pump, 55 and mechanical connections from the adjusting devices to the pumps.

5. In an inking mechanism, the combination 60 of a plurality of pumps for delivering ink under pressure in regulated quantities, means at the pumps for regulating the ink supplied by them, a controller located at a point remote from the pumps for regulating the ink delivered by them, and mechanical 65 connections from the controller to the pumps.

6. In an inking mechanism, the combination of a plurality of pumps for delivering ink under pressure in regulated quantities, means at the pumps for regulating the ink supplied by them, a controller located at a 70 point remote from the pumps, said controller comprising a plurality of adjusting devices, one for each pump, and mechanical connections from the adjusting devices to the pumps. 75

7. In a printing machine, the combination with a plurality of printing couples, of an ink reservoir for each couple, a plurality of plunger pumps in each reservoir for supplying ink under pressure in regulated 80 quantities, a controller for each set of pumps located at a point remote from the reservoir for regulating the quantity of ink delivered by the pumps, and mechanical connections from the pumps to the controller. 85

8. In a printing machine, the combination with a plurality of printing couples, of an ink reservoir for each couple, a plurality of plunger pumps in each reservoir for supplying ink under pressure in regulated 90 quantities, means at each reservoir for regulating the amount of ink supplied by the pumps, a controller, one for each set of pumps, located at a point remote from the reservoir for regulating the ink supplied 95 to the pumps, and mechanical connections from the pumps to the controllers.

9. In a printing machine, the combination with a plurality of printing couples, of an ink reservoir for each couple, a plurality of plunger pumps in each reservoir for supplying ink under pressure in regulated quantities, controllers, one for each set of pumps, located at a point remote from the reservoirs each controller including a 100 plurality of adjusting devices, one for each pump, and mechanical connections from the pumps to the adjusting devices. 105

10. In a printing machine, the combination with a plurality of printing couples, 110 of an ink reservoir for each couple, a plurality of plunger pumps in each reservoir for supplying ink under pressure in regulated quantities, means at the pumps for regulating the quantity of ink delivered by 115 them, controllers, one for each set of pumps, located at a point remote from the reservoir, each controller including a plurality of adjusting devices one for each pump, and mechanical connections from the pumps to 120 the adjusting devices.

11. In an inking mechanism, the combination of a plurality of plunger pumps for delivering a regulated supply of ink under pressure, movable abutments for limiting 125 the suction stroke of the pumps, a controller located at a point remote from the pumps for operating the abutments, and mechanical connections from the abutments to the controller. 130

12. In an inking mechanism, the combination of a plurality of plunger pumps for delivering a regulated supply of ink under pressure, movable abutments for limiting the suction stroke of the pumps, a controller located at a point remote from the pumps, said controller including operating devices for each abutment, and mechanical connections from the abutments to the operating devices of the controller. operating the abutments, and operating wires running from the abutments to the controller.
13. In an inking mechanism, the combination of a plurality of plunger pumps for supplying ink under pressure in regulated quantities, movable abutments for limiting the suction stroke of the pumps, adjusting devices co-operating with the abutments for adjusting them, a controller located at a point remote from the pumps for operating the adjusting devices, and mechanical connections from the controller to the adjusting devices. 18. In an inking mechanism, the combination of a plurality of pumps for delivering ink under pressure, a controller located at a point remote from the pumps for regulating the ink delivered by them, and operating wires running from the pumps to the controller. 70
14. In an inking mechanism, the combination of a plurality of plunger pumps for supplying ink under pressure in regulated quantities, movable abutments for limiting the suction stroke of the pumps, adjusting devices co-operating with the abutments for adjusting them, a controller located at a point remote from the pumps for operating the adjusting devices, and mechanical connections from the controller to the adjusting devices. 19. In an inking mechanism, the combination of a plurality of plunger pumps for supplying ink under pressure, movable abutments for limiting the suction stroke of the pumps, adjusting devices co-operating with the abutments for adjusting them, a controller located at a point remote from the pumps, said controller including adjusting devices, one for each abutment adjusting device, and operating wires running from the abutment adjusting devices to the controller adjusting devices. 75
15. In an inking mechanism, the combination with a plurality of plunger pumps for supplying ink under pressure in regulated quantities, of a plurality of sliding abutments for limiting the suction stroke of the pumps, adjusting screws contacting with the abutments for operating them, pivoted mountings for the screws, a controller located at a point remote from the pumps, said controller including adjusting devices, one adjusting device for each screw, and mechanical connections from the screws to the adjusting devices. 20. In an inking mechanism, the combination of a plurality of separate delivery conduits for delivering an independent supply of ink to different columns or sections of the form, means for feeding ink to the conduits including adjusting devices for regulating the ink fed located adjacent the feeding point, means located at a point remote from the ink feeding means for regulating the ink fed thereto, and mechanical connections from the remote regulating means to the adjacent regulating means. 80
16. In an inking mechanism, the combination of a reservoir, a plurality of plunger pumps in the reservoir for supplying ink in regulated quantities under pressure, a plurality of movable abutments one for each plunger, adjusting devices in the reservoir for adjusting the abutments, a controller located at a point remote from the reservoir, said controller including adjusting devices, and mechanical connections from the controller adjusting devices to the adjusting devices in the reservoir. 21. In an inking mechanism, the combination of a plurality of pumps for delivering ink under pressure in required quantities, means for varying the stroke of the pump plungers, a controller located at a distance from the pumps, and mechanical connections from the controller to the plunger varying means. 100
17. In an inking mechanism, the combination of a plurality of pumps for delivering ink under pressure in regulated quantities, movable abutments for limiting the suction stroke of the pumps, a controller located at a point remote from the pumps for
